UNITED STATES PATENT OFFICE.

GEORGE JAMES, OF LONDON, ENGLAND, ASSIGNOR TO CROSSE & BLACKWELL LIMITED,
OF LONDON, ENGLAND.

DESIGN FOR A JAR.

Application filed September 28, 1925. Serial No. 14,935. Term of patent 14 years.

To all whom it may concern:

Be it known that I, GEORGE JAMES, a subject of the King of Great Britain, residing at 20, Soho Square, in the county of London, England, have invented a new, original, and ornamental Design for a Jar, of which the following is a specification, reference being had to the accompanying drawing, forming a part thereof.

Figure 1 is a perspective view of a jar showing my new design.

Figure 2 is an inverted plan view of the same.

I claim:

The ornamental design for a jar as shown.

GEORGE JAMES.
